CLAIM

The ornamental design for a vehicle rescue device as shown and described.

DESCRIPTION

FIG. 1 is a front, right, bottom perspective view of a vehicle rescue device showing my new design;

FIG. 2 is a back, left, bottom perspective view thereof;

FIG. 3 is a front view thereof;

FIG. 4 is a back view thereof;

FIG. 5 is a left view thereof;

FIG. 6 is a right view thereof;

FIG. 7 is an enlarged top view thereof;

FIG. 8 is an enlarged bottom view thereof;

FIG. 9 is an enlarged view of the encircled area 9 of FIG. 1;

FIG. 10 is an enlarged view of the encircled area 10 of FIG. 2;

FIG. 11 is an enlarged view of the encircled area 11 of FIG. 3; and,

FIG. 12 is an enlarged view of the encircled area 12 of FIG. 4.

The broken lines shown on the drawings depict portions of the vehicle rescue device that form no part of the claimed design. The dot broken lines depict the enlarged view boundaries that do not form part of the claimed design.

1 Claim, 10 Drawing Sheets
